(57) **CLAIM**

The ornamental design for a connector for a snack holder with cup, as shown and described.

DESCRIPTION

FIG. 1 is a first bottom perspective view of our new design for a snack holder with cup;

FIG. 2 is a first bottom exploded view of the embodiment shown in FIG. 1;

FIG. 3 is a second bottom exploded view thereof;

FIG. 4 is a first top exploded view thereof;

FIG. 5 is a first side exploded view thereof;

FIG. 6 is a second side exploded view thereof;

FIG. 7 is a third side exploded view thereof;

FIG. 8 is a fourth side exploded view thereof;

FIG. 9 is a top view thereof; and,

FIG. 10 is a bottom view thereof.

The broken lines shown in the drawing views are included for the purpose of showing environmental structure that forms no part of the claimed design.

1 Claim, 10 Drawing Sheets
